UNITED STATES PATENT OFFICE.

HARRY J. WEBB, OF DETROIT, MICHIGAN.

POLISHING-MACHINE.

Specification of Letters Patent.

Patented May 25, 1915.

1,140,424.

Application filed July 13, 1914. Serial No. 850,538.

To all whom it may concern:

Be it known that I, HARRY J. WEBB, a citizen of the United States of America, residing at Detroit, in the county of Wayne and State of Michigan, have invented certain new and useful Improvements in Polishing-Machines, of which the following is a specification, reference being had therein to the accompanying drawings.

This invention relates to a machine for buffing or polishing the inner surfaces of parabolic or other concave reflectors or articles, and its object is to provide a buffing or polishing element which will contact evenly at all points the surface to be polished and may be adjusted to conform to surfaces having different curvatures.

A further object is to secure an even pressure at all points of the buffer against the surface to be polished and a continuous motion thereof transversely of the plane of a longitudinal axial rotation of the work.

With these and other ends in view, the invention consists in providing a flexible buffing or polishing member and a forming member therefor to cause said buffing member to assume a shape in conformity to the curvature of the surface of the work, and further, in the matters hereinafter more fully set forth, all as pointed out in the appended claims, reference being had to the accompanying drawing in which—

Figure 1 is a side elevation of a machine embodying the invention; Fig. 2 a plan view of the same; Fig. 3, is a sectional detail of a guide and bearing chain; Fig. 4 is an enlarged detail showing a forming block in side elevation, and Fig. 5 is a perspective detail of a portion of a buffing or polishing member.

For convenience of illustration the invention is shown in a suitable form for use in buffing or polishing parabolic reflectors but it will be understood that other arrangements of parts may be made to adapt the same for use in buffing or polishing other articles having concave surfaces. As shown, a suitable base frame or standard 1 is provided with bearings 2 for a shaft 3 upon which is secured a pulley 4 for driving the shaft. A second pulley 5 of larger diameter is also secured upon the shaft 3 and frame members 6 are mounted at each side of said pulley upon the shaft and supported at their forward ends upon a pin 7 carried by a post 8 and projecting through a longitudinal

slot 9 in extension members 10 adjustably secured to the outer sides of the frame members by bolts 11 passing through slots in the extension members.

A forming guide block 12 is pivotally supported between the forward ends of the extension arms 10 by studs 13 on the sides of the block engaging bearing openings in the arms and this block is adjustably held against turning by means of an arm 14 on the block extending rearwardly therefrom and provided with a rod 15 at its rear end which rod is screwthreaded and passed through a block 16 pivoted between the arms 10 with nuts 17 on the rod above and below the block.

The block 12 has an edge face 18, a portion of which is curved to accurately conform to the curve in longitudinal section of the particular reflector 19 which it is desired to buff or polish. The reflector may be held in any suitable manner to be engaged by the buffing member hereinafter described, but it is preferably supported, as shown, by a suitable cap or socket member 20 on the end of a shaft 21 which is supported and rotated in any suitable manner, not shown. In use, the block 12 is held within the reflector and adjusted by means of the arm 14 until that portion of its lower face 18 which is adjacent to the surface of the reflector, is exactly parallel therewith. This edge face 18 of the block serves as a track for a series of rollers 22 which are spaced apart and held in parallelism by sprocket chains 23, the pivot pins of which chains are small shafts or rods 24 each extending through the links of one chain, through the adjacent roll, forming an axle 90 therefor, and through the links of the chain at the opposite side. The rolls are of slightly greater length than the width of the face 18 of the block so that the chains travel adjacent to each side of the block where they are engaged by a pair of sprocket wheels 25 mounted on a shaft 26 located in the center from which is struck the line of the semi-circular forward end of the block. The roller chain comprising the two sprocket 100 chains and rollers, is thus held in place upon the block and guided around its forward end by said wheels, and as said chain is of just sufficient length to loosely encircle the block, it will travel freely upon the edge 105 face thereof.

An endless buffing or polishing belt 27 of

suitable construction is passed over the pulley 5 and over the outer end of the forming block 12 against the roller chain thereon. The rolls 22 thus form a rolling support 5 for the belt upon the block and eliminate friction, the belt being of substantially the same width as the block to engage the rolls between the sprocket chains. The path of travel of that portion of the belt which is 10 adapted to engage the surface to be polished is thus determined by the shape of the edge face of the block, as the belt is drawn tight to force it into firm contact with the chain which is interposed between it and said face. 15 By swinging the block upon its pivot 13, it may be adjusted to the surface to be polished and if it is desired to polish a surface having a widely different curve, a block of the proper outline may be substituted. In 20 operation, the belt is positioned in the longitudinal vertical plane of the axis of the reflector so that it will travel in a plane at right angles to the plane of rotation of the reflector and thus travel across the surface 25 to be polished in a direction longitudinally of the reflector. The semi-circular forward end of the block causes the belt to travel in a semi-circular path where it engages the inner end or bottom of the concave surface 30 of the reflector, the horizontal plane of the axial center of said end being accurately positioned in the horizontal plane of the longitudinal axis of the reflector and its carrying shaft. If found desirable, a small 35 idler pulley 28 carried by an adjustable yoke 29 on the arms 10, may be provided to engage the belt 27 and guide the same adjacent to the upper side and forward end of the forming block. This idler may be adjusted to tighten the belt and the arms 10 40 may be adjusted upon the frame members 6 for the same purpose by loosening the bolts 11.

As shown, the buffing or polishing belt is 45 preferably formed of one or more thicknesses of belting 30 formed of leather or other suitable material to the outer face of which belting strips of fabric 31 are secured by folding a number of these strips upon 50 themselves and passing staples 32 through the fabric at the bottom of the superposed loops, said staples being then driven through the belting and clenched down at the inner side thereof. The tufts or bunches of fabric strips are thus secured in place as close 55 together as possible upon the belt transversely thereof so that the upstanding edges of fabric will form a compact resilient buffing or polishing surface. A flexible polishing belt is thus secured and the upstanding fabric strips are adapted to hold an 60 abrading substance.

Obviously changes may be made in the 65 construction and arrangement of parts without departing from the spirit of my inven-

tion and I do not therefore limit myself to the construction shown.

Having thus fully described my invention what I claim is:—

1. In a machine of the character described, the combination of an endless taut abrasive member, a pulley over which said member travels to drive said member, extension members and a forming member tilt- 70 able at the outer ends of said extension 75 members and over which said member trav- 80 els to cause the same to travel in a path throughout a portion of its length conform- 85 ing to the surface of work.

2. In a machine of the character de- 80 scribed, the combination of an endless abra- 85 sive belt, a drive pulley for the belt, a form- 90 ing member having a surface conforming to the surface of work, and a series of friction reducing devices interposed between 95 said belt and said forming member.

3. In a machine of the character de- 90 scribed, the combination of an abrasive belt, a forming member having a surface curved to conform to the surface of work, an end- 95 less chain having a series of rollers adapted to travel over said surface of the forming member between the belt and said forming member, and means for driving the belt.

4. In a machine of the character de- 95 scribed, the combination of an endless abra- 100 sive belt, a driving pulley for said belt, a pivoted forming member movable to and from said pulley and having a surface curved to correspond with the curvature of the 105 surface of work and over which curved surface the belt is adapted to pass, and means for adjustably supporting said forming member to increase and decrease the abrading area of said belt relative to a piece of work.

5. In a machine of the character de- 110 scribed, the combination of an endless flexi- 115 ble abrasive belt, a driving pulley for said belt, a block having a formed surface over which said belt is adapted to pass, a chain 120 provided with a series of rollers surround- 125 ing said block and passing between said belt and said formed surface.

6. In a machine of the character de- 115 scribed, the combination of an abrasive belt, a driving pulley for said belt, a pivoted forming block having a curved edge surface 120 conforming to the curvature of the surface of work, means for adjustably supporting said block at a distance from said pulley to guide said belt in a curved path throughout the portion of its travel in which it is adapt- 125 ed to be in contact with work, and means carried by the last mentioned means for tilting said pivoted forming block.

7. In a machine for buffing or polishing concave surfaces, the combination of an abrasive belt, a drive pulley for said belt, an oblong forming block having a curved 130

edge surface formed throughout a portion of its length to conform to the curvature of a surface to be polished or buffed, means for pivotally supporting said block at a distance from said pulley, a chain surrounding said block and having a series of rollers running upon said edge surface thereof with the belt in contact with said rollers opposite the said portion of the curved edge surface

5 of the block, and means for adjusting said block upon the pivotal support.

In testimony whereof I affix my signature in presence of two witnesses.

HARRY J. WEBB.
